CONVECTION SECTION

Frank H. Praeger, Merion, Pa., assignor to Alcorn Combustion Company, Philadelphia, Pa., a corporation of Delaware

Application September 23, 1942, Serial No. 459,466

3 Claims. (Cl. 122—356)

My invention relates to fluid heaters of the tubular type and has for an object the provision of a convection section, which for a given number of tubes has a much greater efficiency than heretofore obtained.

In many heaters, particularly those used for the heating of petroleum and its derivatives, the hot gases and/or the products of combustion flow from a fire chamber into a convection section where the transfer of heat from the hot gases to the oil is largely by convection. Usually the convection section consists of a relatively large number of tubes arranged to be washed by the gases, and through the walls of the tubes heat is conducted to the fluid flowing therein. To increase the transfer by convection, such tubes have been provided with fins and gill rings; and other expedients have been resorted to in an endeavor to increase the transfer of heat by convection to the fluid traversing the tubes.

In carrying out my invention in one form thereof, I take advantage of the fact that there is a relation between the amount of heat which may be transferred by radiation and the area of the surface in view of the tubes, which surface is not covered, shielded or obscured by other heat absorbing devices such as tubes. I also take advantage of the radiant heat which is present in the convection gases and provide for transfer thereof directly to the heater tubes. Heretofore, it has been generally believed that after the convection gases have passed beyond the first few rows of convection tubes, transfer of heat by radiation is of inconsequential degree. In accord with my invention, however, the transfer by radiation may be maintained at an unexpectedly high rate and at the same time the transfer by convection may also be maintained at a high rate. In consequence, it is possible to absorb the same amount of heat with a fewer number of tubes, all other conditions being equal.

In the preferred form of my invention, rows of tubes extend in double zig-zag relation through the convection section and side baffles, and central baffles alternating herewith, produce two sinuous paths which follow the junctures of adjacent rows and which cross and recross the zig-zag rows. By providing the angular or zig-zag arrangement of the rows of tubes, a relatively large amount of free space is provided and there is a substantial transfer of heat by radiation to the tubes. By reason of the flow directing function of the baffles there is efficient transfer of heat by convection to the tubes. There are no "dead" spaces. However, I pre-

fer to include one or more rows of tubes between the convection section and the radiant section of the heater arranged in the usual manner in order to avoid overheating of the tubes in the more efficient portion of the convection section which embodies my invention.

For a more complete understanding of my invention, reference is to be had to the accompanying drawing in which:

Fig. 1 is a sectional elevation of a part of a heater embodying my invention in one form thereof;

Fig. 2 is a fractional view of one means of supporting a baffle from a fluid conducting tube;

Fig. 3 is a fractional view of a heater and shows a sectional view of a convection section embodying a preferred form of my invention; and

Fig. 4 is a fractional view of a means for supporting a central baffle from a pair of fluid conducting tubes.

Referring to the drawing, I have shown my invention in one form as applied to a single end-fired heater, that is, one where a plurality of fuel burners 10 are arranged to direct fuel into a plurality of muffles 11, distributed along one side 12 of the heater. Partial combustion of the fuel is completed within the muffles, formed of super-refractory material, and from each muffle still-burning gases and products of combustion are directed generally horizontally across the fire chamber 13 and intermediate a bank of floor tube 14 and an upwardly sloping bank of roof tubes 15. The rear wall 16, together with an upwardly rising wall 17 from the sloping roof 18, form a convection section 19, only a part of which is shown.

The convection gases including the products of combustion are subject to stack-draft and, after their horizontal travel over and above the floor tubes 14, exit from the fire chamber 13 by way of the convection section 19. They first flow between the tubes 20 and thence between the tubes 21 and 22 of additional horizontally disposed rows. The tubes of rows 20—22 are in staggered relation with each other and are subject both to radiant heat from fire chamber 13 and to convection heat.

From the row 22, additional tubes are arranged in rows 23, 24 and 25 which zig-zag through the convection section 19. A baffle 26 extends from the wall 17 outwardly toward the end-tube 23A of the row 23. Between the side or free-end of the baffle 26 and the wall 16 of the convection section, a flow passage is provided.

The combustion gases are confined to flow through that passage and across the angularly disposed row of tubes 23. A second baffle 27 extends from the wall 16 toward the juncture of rows 23 and 24. Hence the gases which have passed between the first few tubes of the row 23 must reverse their direction again to cross the row 23. The gases pass downwardly between tubes 23 and effectively wash the entire circumferential areas of tubes 23. The gases then move around the free end or side of baffle 27 and flow upwardly across the first few tubes of the row 24. Another baffle 28 extends from the wall 17 outwardly toward the juncture of the rows 24 and 25. This baffle redirects the gases so that they must again reverse their direction of flow again to cross the row 24. The above-described flow, by reason of the baffle 29, is repeated and it will be understood that additional rows of tubes and baffles may be provided in the remainder of the convection section (not shown).

It will be observed that gases flowing between adjacent tubes 20, divide around the tubes 21 of the next adjacent row and it is well understood by those skilled in the art that the maximum transfer of heat occurs along relatively restricted fractions of the circumferential areas of each tube. However, in accord with my invention, the flow-directing baffles 26-29 produce a sinuous flow of the gases along the zig-zag arrangement of tubes. The gases cross the tubes of each row, such as 23, in one direction and they then cross the tubes of that row in the opposite direction, and they then recross the tubes of the same row. In this manner the gases effectively wash substantially the entire circumferential areas of each tube. There are no "dead" spaces. There are no tubes located out of the path of the gases.

These desirable results are brought about by reason of the angular relation of each row with respect to the path of the gases when considered in connection with that row. Considering the flow from above the row 23 and below the baffle 27, the gases must flow to the left, thence downwardly between the tubes of the row 23 and thence upwardly around the tubes and a similar circuitous route is followed in the flow of the gases through the rows 24 and 25. The result is convective contact with substantially the entire circumferential area of each convection tube. Besides this intimate, efficient contact of the gases about the tubes, the relatively large tube-free areas have a beneficial effect in re-radiating heat to the tubes. There is also a substantial transfer of heat by radiation from the gases. The combined result of the increased transfer by convection and the transfer by radiation makes possible the use of only 52 convection tubes to perform a heat absorbing duty which heretofore required 80 tubes in a conventional staggered arrangement.

In calculating the heat absorbed in a convection section, determination is first made of the "K" factor, defined as the British thermal units per square foot of heat absorption surface per hour per degree of temperature difference ($^{\circ}$ F.) between the convection gases and the liquid being heated. In accord with my invention, the "K" factor is increased as much as 100%, which means that a great deal more heat is absorbed per square foot of heat absorption surface. The convection bank is much more efficient. It may

be made correspondingly smaller for a given heating duty.

In Fig. 3, I have illustrated a preferred form of my invention as applied to a double end-fired heater having an updraft convection section 30. A heater of the type to which my invention is particularly applicable is illustrated in Fig. 3 of Nash et al. Patent No. 2,229,253.

Referring to Fig. 3 of the drawing, the fractional showing of the sloping roofs 32 and 33 are to be taken as representative of the sloping roofs which extend over a pair of fire chambers. The gases and products of combustion from both fire chambers flow through the central convection section 30 provided with rows of tubes 33, 34 and 35 disposed in the inlet portion. The convection section 30 is subject to stack-draft. The first three rows of tubes 33-35, disposed in staggered relationship, serve the same purposes as described in connection with the rows of tubes 20, 21 and 22 of Fig. 1. In this embodiment of my invention rows of tubes extend through the convection section 30 in double zig-zag relationship. A central baffle 37 extends across the convection section and after the gases have passed through the row 35 of tubes the baffle causes them to divide and to flow outwardly to the sides thereof and towards the respective walls 38 and 39 of the convection section. From the respective walls 38 and 39 rows 40 and 41 of tubes extend angularly toward each other and toward their juncture with rows 42 and 43. The latter rows angularly extend in the opposite direction and respectively back toward the walls 38 and 39. From the juncture of rows 42 and 43 with rows 44 and 45, the rows 44 and 45 extend angularly toward the central part of the convection section 30. Similarly, rows 46 and 48 form a continuation of the zig-zag row on the left hand side of the convection section 30, and rows 47 and 49 form a continuation of the zig-zag row along the right hand part of the convection section 30.

The tubes in the zig-zag rows have their axes disposed along the sides of triangles, the bases of each of which extends longitudinally of the convection section.

This triangular relationship is present in the arrangement of Fig. 1 as well as in Fig. 3. Baffles 50, 51 and 52 extend from the side wall 38 toward the respective apices between the rows or triangle sides 40-42, 44-46 and 48. Similarly baffles 53, 54 and 55 extend from the side wall 39 between the triangle sides 41-43, 45-47 and 49. In the zig-zag rows, additional triangles are formed, with the sides 42-44, 43-45 defining two of them. A central baffle 57 extends from the base of each triangle toward the apex thereof and a baffle 58 performs a like function for the triangular arrangement of rows 46-48, and 47-49.

The gases flow through the convection section 30 in a manner similar to that described for the modification of Fig. 1. However, the gases entering the convection section through the lower three rows 33-35 divide around the opposite sides of baffle 37. The respective streams of gases cross and recross the rows 40 and 41. The streams then join together and pass between 70 and around the tubes disposed at the junctures of rows 40-42 and 41-43. The gases then divide for flow around opposite sides of the baffle 57. They cross and recross the rows 42 and 43 and the foregoing procedure is repeated for each row of tubes.

It will be observed that the baffle 37 is spaced a considerable distance away from, as above, the row of tubes 35. The intervening space provides free flow of the gases and tubes are not located in that region since they would not be efficiently heated.

The baffle 57, as shown in Fig. 4, may be provided with downwardly extending arms 60 and 61 which terminate in semi-circular members 62 and 63 which may nest over tubes 42A and 43A of the rows 42 and 43. If desired, additional supporting means may be provided on the intermediate tube sheets (not shown) normally utilized for the support of the convection tubes. The baffle 37 of Fig. 3 will, of course, be provided with longer extensions for support from two or more of tubes 35.

The side baffles of Figs. 1 and 3 are preferably supported at one end from the side walls of the respective convection sections. The free side or end of each side baffle may be provided with an extension 65, Fig. 2, provided with a semi-circular member 66 for engagement with a tube of one of the rows.

Without affecting the described relation of the tubes with respect to the flow of the convection gases, fluid may be circulated serially through the tubes as illustrated in Fig. 1, or the tubes may be connected for parallel flow as shown in Fig. 3. For example, it may enter the tubes in the convection section through the inlets 70 and 71 and the divided streams may exit through the outlet lines 72 and 73 which may be transfer lines connected to other tubes in the double-end fired heater, such for example as the roof tubes 74 only three of which are illustrated. The tubes may also be connected for other desired flow arrangements such as series-parallel flow.

While I have shown embodiments of my invention, it is to be understood, I do not limit myself thereto, since many modifications may be made and I therefore contemplate by the appended claims to cover any such modifications as fall within the spirit and scope of my invention.

What I claim is:

1. The combination with a heater having walls forming a convection section receiving gases and products of combustion from the heater, of horizontally extending fluid conducting heat absorbing tubes disposed only in rows which extend respectively from opposite walls of said convection section toward the center thereof and back again, the said rows extending in double zigzag relationship through said convection section, side baffles extending from said opposite walls toward

the juncture of adjacent rows, central baffles alternating with said side baffles to produce flow of said gases and products of combustion along double sinuous paths extending through the convection section which cross and recross said zigzag rows, and means interconnecting said tubes of each row for flow of fluid therethrough.

2. The combination with a heater, of walls forming a convection section having an inlet for combustion gases and an outlet subject to stack-draft, a plurality of rows of tubes in staggered relationship disposed across said inlet, a baffle spaced substantially from said tubes in the direction of flow of said gases and extending across the central portion of the convection section for dividing the convection gases, each division thereof flowing around a side of said baffle and adjacent one of said walls, and means extending through said convection section, which comprises a row of horizontal tubes extending from beyond each side of said baffle angularly toward the central portion of said convection section, side baffles extending from each of said walls to restrict flow of gases to between said angularly disposed rows in the region where they approach each other, additional rows of horizontal tubes extending angularly from said central portion toward said walls, and a central baffle for producing divided flow of said gases along paths generally coinciding with said last named angularly disposed rows, the said gases flowing over and around the tubes of said rows.

3. The combination with a heater having walls forming a convection section receiving gases and products of combustion from the heater, of horizontally extending fluid conducting heat absorbing tubes disposed only in rows which extend respectively from opposite walls of said convection section toward the center thereof and back again, the said rows extending in double zigzag relationship through said convection section, side baffles extending from said opposite walls toward the juncture of adjacent rows, central baffles alternating with said side baffles to produce flow of said gases and products of combustion along double sinuous paths extending through the convection section which cross and recross said zigzag rows, each of said central baffles having structure extending downwardly and into supporting engagement with tubes for supporting each of said central baffles therefrom, and means interconnecting said tubes of each row for flow of fluid therethrough.

FRANK H. PRAEGER.
